UNITED STATES PATENT OFFICE.

GODFREY S. MAHN, OF PHILADELPHIA, PENNSYLVANIA.

CONTAINER

1,104,366.

Specification of Letters Patent. Patented July 21, 1914.

Application filed September 26, 1913. Serial No. 791,913.

To all whom it may concern:

Be it known that I, GODFREY S. MAHN, a citizen of the United States, residing at Philadelphia, in the county of Philadelphia and State of Pennsylvania, have invented 5 certain new and useful Improvements in Containers, of which the following is a specification.

My invention relates to improvements in 10 containers, and more particularly to an improved cigar container, the object of the invention being to provide a box consisting of an outer casing and a sliding drawer having improved locking means holding the drawer 15 in the casing and released from locking engagement with the casing by pressure between the thumb and fore-finger of the person desiring to open the box.

A further object is to provide a container 20 of this character which is provided with improved locking means that automatically locks when the drawer is moved into the casing, and is securely held thereby against possibility of accidental opening.

With these and other objects in view, the 25 invention consists in certain novel features of construction and combinations and arrangements of parts as will be more fully hereinafter described and pointed out in the 30 claim.

In the accompanying drawings: Figure 1 is a perspective view illustrating my improvements, showing the thumb and fore-finger of the operator in position to 35 press the drawer and release the same from locking engagement with the casing. Fig. 2 is a view in transverse longitudinal section, and Fig. 3 is a view in vertical longitudinal section.

1 represents the outer casing and 2 the sliding drawer of my improved box or container. Both casing and drawer are pref- 40 erably of metal or other elastic material and are of general oblong shape. The casing 1 has a top and bottom 3 and 4 respectively 45 connected by sides 5, and one end 6, the other end of the casing open for the entrance and exit of the drawer 2.

The drawer 2 has a bottom 7, sides 8, and 50 ends 9, but is provided with an open top so that the cigars or other articles may be readily packed therein. The sides 5 of cas-

ing 1 are recessed at their ends as shown at 10. These recesses extend from the open end of the casing, and longitudinally of the 55 casing, a distance sufficient to permit a free grip of the sides 8 of the drawer 2 between the thumb and fore-finger of the operator when the drawer is in its closed position as indicated clearly in Fig. 1.

The sides 5 of casing 1, adjacent the inner 60 ends of the recess 10, are formed with outwardly pressed portions 11, which form on the inner face of the casing, recesses to receive similarly shaped projections 12 forced 65 outwardly from the sides 8 of the drawer 2. These projecting portions 11 and 12 interlock when the drawer is in its closed position, so that the drawer will not accidentally fall open.

To open the box, the operator places his 70 thumb and fore-finger in the recesses 10, and presses the sides 8 of drawer 2 toward each other, withdrawing the projections 12 from the projections 11, and enabling the drawer 75 to be drawn out. As a matter of fact, the operation of releasing the lock and moving the drawer is simultaneous, as the operator may press the sides of the drawer inwardly and withdraw it at the same time. When 80 the drawer is forced into the casing, its enlargements 12, by reason of their rounded formation in cross section, will press the sides 5 of the casing outwardly, until they 85 reach the projections 11, when they will spring into locked engagement therewith.

Various slight changes might be made in the general form and arrangement of parts described without departing from my invention, and hence I do not limit myself to 90 the precise details set forth, but consider myself at liberty to make such changes and alterations as fairly fall within the spirit and scope of the appended claim.

Having thus described my invention, what 95 I claim as new and desire to secure by Letters Patent is:

A cigar box formed of sheet metal comprising a rectangular drawer having an open top and closed bottom, sides and ends, a casing 100 conforming in shape and size to the drawer adapted to snugly receive the drawer and having one open end, said casing at its sides having recesses extending inwardly

from its open end adapted to receive the thumb and finger of an operator to compress the sides of the drawer toward each other, said drawer and casing having interlocking means separated by the movement of the sides of the drawer toward each other, substantially as described.

In testimony whereof I have signed my name to this specification in the presence of two subscribing witnesses.

GODFREY S. MAHN.
